UNITED STATES PATENT OFFICE

105,790

DESIGN FOR A FISHING REEL

Joseph A. Coxe, Los Angeles, Calif.

Application August 31, 1936, Serial No. 64,648

Term of patent 14 years

To whom it may concern:

Be it known that I, Joseph A. Coxe, a citizen of the United States, residing at Los Angeles, Los Angeles county, California, have invented a new, original, and ornamental Design for a Fishing Reel, of which the following is a specification.

The design is shown in the accompanying drawings, which form a part hereof, and in which:

Figure 1 is a perspective view showing the crank end of the reel; and

Figure 2 is a perspective view showing the opposite end of the reel.

The dominant and characteristic features of the design are the crescent shaped harness clips pivoted on certain of the tapered pillars, and the interconnecting of the clips in pairs by crossed rods which lie close beside the tapered pillars but which are not themselves tapered.

I claim:

The ornamental design for a fishing reel, substantially as shown and described.

JOSEPH A. COXE.
